UNITED STATES PATENT OFFICE.

HARRY N. LOWENTHAL, OF PHILADELPHIA, PENNSYLVANIA, ASSIGNOR TO R. H. BEAUMONT COMPANY, OF PHILADELPHIA, PENNSYLVANIA, A CORPORATION OF PENNSYLVANIA.

BY-PASS FOR FEEDING MECHANISM FOR CRUSHERS.

Application filed August 18, 1921. Serial No. 493,294.

To all whom it may concern:

Be it known that I, HARRY N. LOWENTHAL, a citizen of the United States, residing in Philadelphia, Pennsylvania, have invented 5 certain Improvements in a By-Pass for Feeding Mechanism for Crushers, of which the following is a specification.

This device relates to a feeding device for crushers for crushing coal, and other granular material, as it is passed from a hopper 10 into a bin, or other receptacle.

The object of my invention is to provide a simple means for by-passing the crushing rolls when it is not desired to crush coal, or 15 other material, as it passes from the hopper to the bin, or other receptacle.

In the accompanying drawings:

Fig. 1 is a sectional elevation illustrating 20 my invention;

Fig. 2 is a front elevation;

Fig. 3 is a perspective view of the reciprocating feeding device with one of the plates removed, and

Fig. 4 is an enlarged sectional view of the 25 feed plate.

Referring to the drawings, 1 is the frame of the structure made in any suitable manner. 2 is the hopper. 3 is a bin, or other receptacle, to receive the coal, or other material, as it flows from the hopper. 4, 4 are two crushing rolls placed a given distance apart and driven in any suitable manner. 5 is a reciprocating feeding plate for feeding the coal, or other material, from the hopper to the space between the rolls so that, as the coal flows from the end of the plate, it will pass through the rolls and will be crushed to the proper degree. This feeding plate, in the present instance, is reciprocated by means 35 of an eccentric 6 on the shaft 7 of one of the rolls 4, and an eccentric rod 8 has a strap ex-

tending around the eccentric and is pivotally connected, at 9, to the plate. In the present instance, the plate has rollers 10 adapted to rails 11 secured to the frame of 45 the structure. Under the hopper 2 is an inclined plate 12 for guiding the material onto the feeding plate 5. Directly below the feeding plate is a second hopper 13, which has a chute 14 for directing material into the bin, 50 or other receptacle 3. The feeding plate 5 is made as shown in Fig. 3, and has a detachable section 15, which closes the opening 16. When the plate 15 is in the position shown in Fig. 1, the material passing from the hopper 2 is discharged by the feeding plate between the rolls so that it will be crushed in its passage to the bin, but, when it is desired to feed material from the hopper to the bin without crushing, the plate 15 is detached, 60 leaving the opening 16 directly below the hopper so that the material will flow from the hopper 2 through the opening 16 in the feeding plate 5 into the hopper 13 and through the chute 14 into the bin. 65

In some instances, it may be desirable to disconnect the eccentric 8, but the rod need not be disconnected as the feeding plate can be reciprocated without feeding material to the rolls when the detachable plate 15 is 70 removed.

I claim:

The combination of a pair of crushing rolls; a hopper above said rolls; a bin, or other receptacle, below the rolls; and a reciprocating feeding plate for feeding material from the hopper to the rolls, said feeding plate having a detachable section, which, when removed, will cause the material to bypass the crushing rolls and flow directly into 80 the bin, or other receptacle.

HARRY N. LOWENTHAL.
